2 Claims. (Cl. 82—36)

My invention has for its object an adjustable assembly of parts forming a tool-holder for lathes and the like machine-tools, said assembly allowing the adjustment as required of the location of the tool with reference to the transverse slideway on the lathe. For this purpose, said tool-holder includes a shoe adapted to be positioned at any desired point of the transverse slideway either to the front or to the rear of the part to be machined, which shoe may carry one or more tools fitted in any desired position between said shoe and a carrier plate which is secured to the shoe by means of vertical threaded ties extending through openings selected as required out of a series of openings formed in said plate and screwed for instance into nuts adjustably positioned at selected points of transverse grooves formed in the shoe. Removable tubular stays surround a number of said ties so as to hold the shoe spaced with reference to the carrier plate while the actual tools are held by screws and shims at the desired locations.

I have illustrated, by way of example, in the accompanying drawing a preferred embodiment of a tool-holder according to my invention. In said drawing:

FIGS. 1 and 2 are elevational views of a tool-holder fitted on the slideway respectively in partly sectional, partly elevational view and in end view;

FIG. 3 is a view thereof as seen from above;

FIG. 4 illustrates a modification seen endwise as in the case of FIG. 2.

In the tool-holder illustrated, the shoe 1 is secured by a clamp 4 at any desired point to the upper longitudinal dove-tailed surface of the transverse slideway.

Said shoe is adapted to receive at any point of its surface a tool 12 or 13 and may be positioned to either side of the part 5 to be machined. I have illustrated at 1' in dot-and-dash lines a second position which may be occupied by the shoe together with the other part of the tool-holder, said second position lying to the right-hand side of the part 5 whereas the position illustrated in solid lines and described hereinabove lies to the left-hand side thereof.

Above the shoe 1, there extends the plate 8 of the tool-holder over the tools 12 and 13 to be secured between said plate and the shoe in any desired position. The plate 8 is secured to the shoe 1 by means of vertical threaded ties 11 extending through the plate and screwed into the shoe 1 for instance through engagement with the nuts 7 adapted to slide in the transverse T-shaped grooves 6 and 6' formed in the shoe in parallelism with the axis of the part 5 to be machined. Said nuts are held in position at selected points of the grooves under the action of the frictional effect obtained by the screwing of the corresponding ties.

Said ties are reinforced by removable tubular stays 9 of a suitable length which hold the plate 8 and shoe 1 apart with the desired predetermined spacing.

In order to cut out any bending or deformation of the tool-holder, further ties 16 which are not provided with stays such as 9 extend also through openings in the plate 8 and are screwed into further nuts 7' carried inside the grooves 6 or 6' of the shoe in the same manner as in the case of the nuts 7.

2

The tools such as 12 or 13 are held against shifting by screws 14 extending through the plate 8 and acting on the tools with the interposition of the shims 15. The tools may thus be set fast with reference to the tool-holder at any suitable position outside the ties and stays, while their level is adjusted by suitably selecting the thickness of the shims 15.

FIG. 3 is a plan view showing the relative location of the openings formed in the plate 8 and through which the ties 11, 16 are to be fitted. These openings are distributed along transverse lines the spacing of which must be equal to that of the grooves 6 and 6' formed in the shoe.

In FIG. 4 I have illustrated a modification wherein the ties which are associated with stays are arranged in the vicinity of the opposite transverse edges of the plate 8 and of the shoe 1.

Obviously, the various members of the tool-holder described may be replaced by equivalent members playing the same part without widening thereby the scope of the invention as defined in the accompanying claims.

What I claim is:

1. A tool-holder for lathes and the like machine-tools provided with a transverse slideway, said tool-holder comprising a shoe adapted to be secured at any desired point of the length of the transverse slideway extending to the front and to the rear of the part to be machined, said shoe being provided with a plurality of transverse T-shaped grooves perpendicular to the slideway, a plate extending above the shoe and provided with openings distributed along parallel lines registering vertically with said grooves, a plurality of vertical headed stays extending through selected openings of said plate and the lower ends of which are threaded, nuts engaging slidably the transverse grooves of the shoe and screwed over the lower ends of the stays, at least one tool system fitted between the plate and the shoe, shims inserted between the upper ends of the tool systems and the plate to clamp said tool systems in the desired position against the shoe and the shims and plate against the heads of the stays and screws holding the shims in position and extending through the plate.

2. A tool-holder for lathes and the like machine-tools provided with a transverse slideway, said tool-holder comprising a shoe adapted to be secured at any desired point of the length of the transverse slideway extending to the front and to the rear of the part to be machined, said shoe being provided with a plurality of transverse T-shaped grooves perpendicular to the slideway, a plate extending above the shoe and provided with openings distributed along parallel lines registering vertically with said grooves, a plurality of vertical headed stays extending through selected openings of said plate and the lower ends of which are threaded, nuts engaging slidably the transverse grooves of the shoe and screwed over the lower ends of the stays, at least one tool system fitted between the plate and the shoe, shims inserted between the upper ends of the tool systems and the plate to clamp said tool systems in the desired position against the shoe and the shims and plate against the heads of the stays, removable tubular stays surrounding a number of the ties and fitted between the plate and the shoe, and screws holding the shims in position and extending through the plate.
